UNITED STATES PATENT OFFICE.

RICHARD LUNDQVIST, OF LAGUNA DE TERMINOS, MEXICO.

LAUNDRY-LIST INDICATOR.

SPECIFICATION forming part of Letters Patent No. 570,819, dated October 27, 1896.

Application filed December 19, 1895. Serial No. 572,640. (No model.)

To all whom it may concern:

Be it known that I, RICHARD LUNDQVIST, of Laguna de Terminos, State of Campeche, Republic of Mexico, have invented a new and 5 Improved Record-List for Laundries, of which the following is a full, clear, and exact description.

My invention relates to a record-list especially adapted for recording the number of 10 pieces sent to a laundry or delivered to be washed, but which is likewise applicable as a record for orders given for various articles or for various articles delivered.

The object of the invention is to provide a 15 record-list upon which the names of various articles may be produced and prominently shown, and likewise to provide the said list with inscribing-surfaces capable of being written upon with a lead or a slate pencil, a 20 crayon, or the like, the said inscribing-surfaces being opposite the name of each article on the record-list, and whereby also another inscribing-surface will be produced upon the 25 said record-list adapted to receive a date.

Another object of the invention is to so 30 mount the record-list upon a handle that the name of any particular article may be brought in a position over the handle which will facilitate the placing of a number in the inscrib-

35 The invention consists in the novel construction and combination of the several parts, as will be hereinafter fully set forth, and pointed out in the claim.

Reference is to be had to the accompanying 40 drawings, forming a part of this specification, in which similar characters of reference indicate corresponding parts in all the figures.

Figure 1 is a front elevation of the improved 45 record-list. Fig. 2 is a longitudinal section through the same, taken practically on the line 2 2 of Fig. 1; and Fig. 3 is a rear elevation of the said record-list, being drawn upon a reduced scale.

In carrying out the invention, the record-list A may be made of pasteboard, celluloid, or any other desired material, and it may be 50 of any desired shape. Preferably, however, it is given a circular form, and in the central portion of the said list upon its front face an inscribing-surface B is produced by roughening the said surface if the list is made of cellul-

loid or applying a silicate or equivalent facing thereto if the list is made of cardboard or a like material, and upon the margin of the 55 list upon its front face a second inscribing-surface C is made in substantially the same manner as the central one.

In the space between the two inscribing-surfaces the names of various articles, such as 60 "Wearing-apparel," "Table and bed linen," &c., are printed or otherwise produced, and the said names are arranged ordinarily in lines radially from the central space, and preferably a panel D is provided on the list 65 between the two inscribing-surfaces for the name of each article.

The names of the articles are to be permanently made on the record-list, and the date 70 on which the articles are delivered to the laundry, for example, is to be written upon the central inscribing-surface, and the number of pieces of each article is written upon the outer inscribing-surfaces opposite the names of the articles, as shown in Fig. 1, and the 75 numbers and likewise the date are preferably written in with a lead-pencil, a slate-pencil, or a crayon, in order that when the order has been filled or the pieces of the laundry returned the number of said pieces may be 80 erased.

Preferably and as a matter of convenience the record-list is mounted to turn upon one 85 end portion of a handle E, being pivotally connected thereto by means of an eyelet E' or the equivalent thereof, and in order that the list may be steadied as it is revolved and prevented from revolving too rapidly a lug F is formed upon the front face of the handle, and this lug extends outward and upward, being 90 of angular construction, to receive the margin of the list. An opening G is also usually made in the handle in order that the list may be hung up when desired.

An advertisement of any approved character 95 may be produced on the back of the list, as shown in Fig. 3, or this back portion may be decorated in any approved manner or may contain a list of articles different from the list on the front, in which event the inscribing-surfaces are produced on the back also.

Having thus described my invention, I claim as new and desire to secure by Letters Patent—

A record-list, comprising a circular board having a central circular inscribing-surface, an annular marginal inscribing-surface and radial panels in the space between the said inscribing-surfaces, the said panels having the names of the articles produced thereon, and a handle to the upper end of which the

board is pivoted, said handle having a lug projecting over the margin of the board, substantially as herein shown and described.

RICHARD LUNDQVIST.
